UNITED STATES PATENT OFFICE.

EDWARD STICKLER, OF ONALASKA, WISCONSIN.

TWISTING-MACHINE.

No. 894,860.

Specification of Letters Patent.

Patented Aug. 4, 1908.

Application filed December 31, 1906. Serial No. 350,277.

To all whom it may concern:

Be it known that I, EDWARD STICKLER, a citizen of the United States, residing at Onalaska, in the county of La Crosse and State of Wisconsin, have invented a new and useful Twisting-Machine, of which the following is a specification.

This invention relates to means for twisting yarn, twine, cord, rope and the like.

The principal object is to provide novel means of a simple nature, wherein the winding and twisting means are operated in such a manner that as spools, bobbins or other holders fill, their speed will be automatically and properly varied with respect to the twisting means so as to avoid all drag, insure the same tension upon the material to be twisted, and thus insure the same twist throughout the entire length, thereby securing a uniform product.

Another and important object is to provide novel means, whereby when the spools or holders are filled, the machine will be automatically stopped, thereby preventing overwinding and permitting the removal of the filled holders and the introduction of the empty ones.

A still further object is to provide simple and novel means for insuring the proper operation of the twisting devices, avoiding any danger of their slipping and to provide tension mechanism for the strands, that is readily adjustable to secure the proper resistance and to avoid too free feed, to provide mechanism that can be stopped at any time when it is found convenient or necessary, and to provide mechanism whereby the twist of the yarn can be varied as desired.

The preferred form of construction is illustrated in the accompanying drawings, wherein:

Figure 1 is a front elevation of the machine. Fig. 2 is a rear elevation of the machine. Fig. 3 is a side elevation thereof. Fig. 4 is a top plan view. Fig. 5 is a detail perspective view of the automatic stopping mechanism. Fig. 6 is a detail sectional view on the line 6-6 of Fig. 2.

Similar reference numerals designate corresponding parts in all the figures of the drawings.

In the embodiment illustrated, a suitable supporting frame 7 is employed, in the front portion of which is mounted a vertically reciprocating carrier frame comprising horizontal bars 8 connected by tie rods 9. The

ends of the bars 8 are provided with notches 10 that receive guide rods 11 secured to the frame. Upon the reciprocating frame are journaled a plurality of winding devices, consisting of upright spindles 12 that project above the upper bar 8 to receive spools 13 or other holders for the completed material. These spindles 12 are provided between the bars 8 of the reciprocating frame with pulleys 14, around which pass belts 15 that also pass around a drum 16, carried by a secondary drive shaft 17, journaled in the frame and projecting beyond the opposite sides thereof.

Journalized in a pair of spaced bars 7^a of the main frame 7 are a plurality of twisting devices or fliers that are associated with the winding means above described, and comprise spaced depending arms 18 carried by upright tubular shafts 19, the arms of each flier being located on opposite sides of one of the spindles 12 and having eyes 20 formed at their lower ends. The tubular shafts 19 of the fliers are provided between the bars 7^a with oblique toothed gears 21, and meshing with these gears are larger oblique toothed gears 22 carried by a horizontally disposed main driving shaft 23 that is also journaled in the main frame 7, and projects beyond the opposite sides thereof. The main drive shaft 23 is designed to be operated from any suitable source of power, transmitted by a belt (not shown), which operates upon loose and tight pulleys 24 and 25 mounted on one of the projecting ends of the shaft 23. The power imparted to the drive shaft 23 is transmitted to the secondary shaft 17, through the medium of a crossed belt 26 that operates upon oppositely disposed cone pulleys 27 secured to the shafts 17 and 23 on the opposite side of the machine to the loose and tight pulleys 24 and 25.

The reciprocating movement of the carrier frame 8-9 is secured by the following mechanism. A shaft 28, journaled on the main frame, is provided with a pair of heart-shaped cams 29 that operate against the inner ends of a pair of levers 30, said levers being fulcrumed, as shown at 31 between their ends. The outer ends of the levers rest against the under side of the reciprocating frame. One end of the shaft 28 carries a worm wheel 32, and meshing therewith is a worm 33 carried by a countershaft 34 journaled on one side of the frame and having a worm wheel 35 on its rear end. A worm 36, carried by the secondary shaft 17 co-operates

with the worm 35 to rotate the same, and thereby operates the countershaft. This countershaft, in turn through the gearing described, rotates the shaft 28 and the heart-shaped cams 29, consequently swinging the levers 30, alternately raising the carrier frame, and permitting its downward movement.

For the purpose of automatically shifting the belt 26 on the cone pulleys 27 and thereby automatically effecting the relative variable movements of the winding and twisting devices, the following mechanism is employed. A reciprocating rod 37 is mounted in the supporting frame 7, and carries at one end, a yoke 38 that engages the crossed belt 26. The rod 37 is held against rotation by a screw 39 mounted in the supporting frame and engaging in a slot 40 in said rod. Upon the rod is loosely journaled a spiral cam 41, and operating against the spiral face of said cam, is an arm 42 fixed to the rod 37 by a set screw 43. A spring 44, surrounding a portion of the rod, has one end secured thereto, as shown at 45, while its other end is fastened 25 to a hanger bracket 46, depending from the supporting frame. This spring serves to hold the inner end of the arm 42 against the spiral face of the cam, and yet permits the outward movement of the rod, as will be apparent. Fulcrumed between its ends on one side of the frame, is a lever 47. The rear end of this lever carries a dog 48 coöperating with a ratchet wheel 49, connected to the spiral cam 41. A loose dog 50 engages the ratchet 35 wheel and prevents the retrograde movement of the same, and consequently of the cam. The front end of the lever 47 is located above and in the path of movement of the carrier frame 8-9 so that when said carrier frame is 40 moved upwardly, the front end of the lever will be moved in a corresponding direction, and the dog 48 will ride loosely over one or more teeth of the ratchet wheel 49. The return movement of the lever 47 is secured by 45 means of a weight 51, adjustably mounted on the front arm of the lever 47, and it will be evident that upon the downward movement of the lever, the dog will interlock with the teeth of the ratchet wheel 49 and effect a partial rotation of said wheel. The downward movement of the lever is stopped by an adjustable screw 52, adjustably carried by the frame and having its upper end disposed in the path of movement of the front end of the 55 lever.

Associated with the loose and tight pulleys 24 and 25 is a belt shifting yoke 53, carried by a horizontally disposed bell crank lever 54 pivoted as shown at 55 to the top of the machine. The outward movement of this lever is limited by a stop spring 56 secured to the top of the machine and having a down-set portion 57 that frictionally engages said lever to hold it in a predetermined position. 60 The bell crank lever 54, and consequently the

belt shifting yoke 53 is moved by a crank arm 58, the upper end of which is loosely engaged in an opening in the lever 54, the lower end being fixed to a rock shaft 59, journaled on the adjacent side of the machine. This rock shaft has another upstanding crank arm 60 the upper end of which is disposed in the path of movement of a reciprocating plunger rod 61, slidably mounted on the rear upper end of the machine. A coiled spring 62 urges said rod outwardly, but it is normally held against outward movement by a sliding and swinging latch 63, the upper offset end 64 of which engages in a notch 65, formed in the rear side of the rod, said rod 80 having an upwardly inclined portion 66 disposed directly in rear of the notch. The lower end of the latch 63 extends between a pair of guides 67, and is disposed in the path of movement of a pin or projection 68, fixed to the inner side of the ratchet wheel 49. A spring 69 bears against the upper end of the latch 63 to hold it in the notch 65. An actuating handle 70 is preferably secured to the front end of the rock shaft 59, and affords 90 convenient means, whereby the belt can be manually shifted from the loose to the tight pulley or vice versa.

The material to be twisted and wound, is preferably mounted on spools or spindles 71 95 that are journaled on upstanding stems 72, which stems are mounted in a carrier frame 73 fastened upon the top of the machine. Between this holder and the twisting devices or fliers, is a tension frame, the same consisting of spaced rods 74 connected at their ends to cross bars 75. The frame thus formed, is rotatably mounted in a pair of standards 76 secured to the top of the frame, and is normally held against rotation, and in different 100 fixed positions by nuts 77 that bear against the upper ends of the standards.

The operation of the machine may be briefly described as follows. When the winding and twisting operations are first 110 started, the cam 41 is so arranged that the arm 42 bears against its innermost end, and consequently the belt 26 will be upon the inner ends of the cone pulleys 27. If now, the shifter 53 is moved by the handle 70, so that 115 the belt will be upon the tight pulley 25, it will be evident that the various mechanisms will be thrown into operation, that is to say, the spools or holders will be rotated, and the fliers will also be rotated, thereby twisting 120 the strands, as they come from the spindles 72, and winding them upon the spools. At the same time, the carrier frame 8-9 will be reciprocated. This movement will cause the swinging of the lever 47, effecting a step-by-step rotation of the ratchet wheel 49, and the rotation of the cam 41. As a result, the belt 26 will be gradually moved toward the outer ends of the pulleys 27 as long as the machine is in operation, thus progressively 125 130

varying the relative rates of speed of the fliers, and winding devices. The yarn, cord, twine or other material is thus wound evenly from one end of each spool to the other and the relative change of speeds insures the proper tension and uniform twist of the same. When the spools are filled, the cam 41 has made one complete revolution, and therefore the arm 42 will be forced back to the inner end of the spiral face. At the same time, the pin or projection 68 will strike the latch 63, swinging it so that its upper end will disengage from the notch 65, thereby releasing the rod or bar 61. The spring 62 will therefore force said rod or bar outwardly, swinging the crank arm 60, operating the rock shaft 59, swinging the crank arm 58, and thus shifting the belt back to the loose pulley. At the same time, the latch 63 will be raised by the inclined portion 66 of the rod or bar and said pin will move beyond the same. It will thus be evident that after the filled spools have been removed, and empty ones placed in position, the machine can be again started by merely throwing the belt shifter 53, so that the driving belt will be moved on to the tight pulley, whereupon the operation will be repeated.

One of the important features of the invention relates to the means, whereby the mechanism may be made to produce various kinds of twists, said mechanism being such that the twist of the yarn or other material can be varied from one turn, to two hundred turns, 30 to the inch, depending upon the finish and character of the yarn or material. This is done by loosening the thumb screw 43 and adjusting the shifter rod 37 in one direction, or the other, thus moving the belt 26 on the cones 27, so as to change the intake of the 35 yarn, or in other words, vary the speed of rotation of the winding devices with respect to the twisters. Another very important feature is the positive spiral gear drives for the 40 fliers. As is well known to those skilled in the art, bands are ordinarily used, and while bands may be employed in connection with the other features of this machine, the spiral 45 gearing is advantageous, particularly in heavy work, for bands are liable to slip, and thus produce variable twists in the yarn, but by the mechanism set forth, the twisting action is made positive. The frame 74—75 is 50 also an important feature, for by means of it, the proper tension can be placed on the yarn passed through the same, and said frame constitutes very simple means for varying this 55 tension.

From the foregoing, it is thought that the construction, operation, and many advantages of the herein described invention will be apparent to those skilled in the art, without further description, and it will be understood that various changes in the size, shape, 60 proportion, and minor details of construc-

tion, may be resorted to without departing from the spirit or sacrificing any of the advantages of the invention.

Having thus fully described my invention, what I claim as new, and desire to secure by Letters Patent, is:—

1. In mechanism of the character described, the combination with winding devices and twisting devices delivering thereto, of a movable support for one of the devices, means for driving the devices at relatively variable rates of speed, and automatic mechanism for effecting a variation in such rates of speed, said mechanism including a swinging actuating lever engaged with and swung by the support, and speed changing means operated by the lever.

2. In mechanism of the character described, the combination with winding devices and twisting devices delivering thereto, of a movable support for one of the devices, means for driving the devices at relatively variable rates of speed, automatic mechanism for effecting a variation in such rates of speed, said mechanism including speed changing mechanism associated with the driving means of one of the devices, a cam, a device for operating the speed varying mechanism, said device being engaged with and operated by the cam, and means operated by the movable support for effecting the movement of the cam.

3. In mechanism of the character described, the combination with winding devices and twisting devices delivering thereto, of a movable support for one of the devices, means for driving the devices at relatively variable rates of speed, and automatic mechanism for effecting a variation in such rates of speed, said mechanism including speed changing mechanism associated with the driving means of one of the devices, a cam, a device for operating the speed changing mechanism, said device being engaged with and operated by the cam, and a swinging lever for effecting an intermittent movement of the cam, said lever being engaged with and swung by the support on its movement.

4. In mechanism of the character described, the combination with winding means, of twisting means delivering thereto, means for driving said winding and twisting means at relatively variable rates of speed, speed changing mechanism associated with the driving means, a longitudinally movable device for operating the speed changing mechanism, actuating means for the device movably mounted on and supported by said device, said actuating means being held against longitudinal movement with the device, and mechanism for moving the actuating means.

5. In mechanism of the character described, the combination with winding means, of twisting means delivering thereto,

means for driving said winding and twisting means at relatively variable rates of speed, speed changing mechanism associated with the driving means, a longitudinally movable 5 device for operating the speed changing mechanism, an actuating member for the device rotatably mounted thereon and permitting its longitudinal movement, and means for rotating said member.

10 6. In mechanism of the character described the combination with a winding device, of a twisting device delivering thereto, mechanism for driving the devices at relatively variable rates of speed, and automatic 15 means for effecting the variation in said rates of speed, said mechanism including a longitudinally movable rod, a cam rotatably mounted on the rod, a device carried by the rod and engaged with the cam, and 20 means for rotating the cam.

7. In mechanism of the character described, the combination with a winding device, of a twisting device delivering thereto, mechanism for driving the devices at relatively variable rates of speed, and automatic 25 means for effecting the variation in said rates of speed, said means including a longitudinally movable rod, a cam rotatably mounted thereon, a ratchet wheel secured to the cam, 30 a lever having a dog that operates on the ratchet wheel, and means for swinging the lever.

8. In mechanism of the character described, the combination with twisting devices and winding devices delivering to the twisting devices, of a movable frame carrying one of the devices, mechanism for operating the devices at relatively variable rates of speed, and automatic means for moving 35 40 said mechanism to relatively vary said rates of speed, said automatic means including a cam, and means operated by the movable frame for intermittently moving the cam.

9. In mechanism of the character described, the combination with a support, of a reciprocating frame, a winding device mounted upon the frame, a flier coacting with the winding device and delivering the twisted material thereto, means for rotating said flier, means for rotating the winding device, a variable speed driving device between the rotating means of the winding device and of 45 50 55 said flier, said device including a pair of cone pulleys and a connecting belt, a yoke for shifting the device, a spiral cam for operating the yoke, a lever actuated by the reciprocating frame, and a pawl and ratchet connection between the lever and the cam.

10. In mechanism of the character described, the combination with a support, of a reciprocating frame, a winding device mounted upon the frame, a flier coacting with the winding device, means for rotating the flier, means for rotating the winding device, a variable speed driving device between 60 65

the rotating means of the driving device and of the flier, said variable speed device including a pair of cone pulleys and a connecting belt, shifting means coöperating with the belt, a spiral cam for operating the shifting means, a lever actuated by the reciprocating frame, a pawl mounted upon the lever, a ratchet wheel carried by the cam and engaged by said pawl, and means for limiting the movement of the lever to rotate the cam. 70 75

11. In mechanism of the character described, the combination with a support, of a reciprocating frame, a spindle mounted upon the frame, a flier coacting with the spindle, a main drive shaft, gearing between the shaft and flier, a secondary shaft, gearing connecting the secondary shaft and the spindle, cone pulleys mounted upon the main and secondary shafts, a cross belt connection between the cone pulleys, a sliding rod, a yoke upon said rod engaged with the belt, a spiral cam rotatably mounted upon the rod, an arm upon said rod, a spring for holding said arm in engagement with the cam, a ratchet wheel carried by the cam, a lever actuated by the reciprocating frame, and a pawl actuated by the lever and engaged with the ratchet wheel. 80 85 90 95

12. In mechanism of the character described, the combination with winding means, of twisting means associated therewith, mechanism for driving the winding means, mechanism for driving the twisting means, automatic means for progressively varying the relative speed of the driving mechanisms 100 while the twisting and winding means is in operation, and means operated by the speed varying means for automatically stopping the twisting and winding means when said speed varying means has reached a predetermined position. 105

13. In mechanism of the character described, the combination with winding means, of twisting means delivering thereto, automatic means for operating said means and progressively varying the speed of one with respect to the other during the operation of said means, and mechanism controlled by the speed varying means for automatically stopping the winding and twisting means 110 115 after a predetermined movement of the same.

14. In mechanism of the character described, the combination with a rotatable winding device, of a rotatable twisting device associated therewith and delivering the twisted material thereto, variable speed mechanism for rotating said devices, means for actuating the variable speed mechanism to relatively vary the rates of speed of the 120 125 devices, and automatic stop mechanism controlled by the actuating means for the speed varying mechanism.

15. In mechanism of the character described, the combination with twisting 130

- means, of a driving element therefor, winding means associated with and delivering to the twisting means, a driving element for the winding means, variable speed mechanism 5 for imparting the motion of one of said elements to the other, means for actuating said variable speed mechanism, fixed and loose pulleys upon one of said driving elements, a belt shifting device coacting with the pulleys, a spring actuated bar for operating the belt shifting device, and a latch arranged to normally lock the bar against movement and to be actuated by the actuating means for the variable speed mechanism to release said bar.
16. In mechanism of the character described, the combination with a reciprocatory frame, of a winding device mounted thereon, a flier coacting with and delivering to the winding device, a main drive shaft, driving connections between the shaft and the flier, a secondary drive shaft, driving connections between the latter shaft and the winding device, variable speed mechanism between the shafts, controlling means for moving said 25 variable speed mechanism to vary the relative speeds of the shafts, means actuated by the reciprocatory frame for operating the controlling means of said variable speed mechanism, stop mechanism for the main drive shaft, including a belt shifter, and means actuated from the reciprocatory frame for effecting the operation of the belt shifting device.
17. In mechanism of the character described, the combination with a reciprocatory spindle frame, of a spindle upon said frame, a flier coacting with the spindle, a main drive shaft, driving connections between said shaft and said flier, a secondary 30 drive shaft, driving connections between the latter shaft and the spindle, variable speed mechanism between the shafts, means for controlling said variable speed mechanism, means actuated by the reciprocatory spindle frame for operating the controlling means of said variable speed driving device, fixed and loose pulleys upon the main drive shaft, a belt shifting device coacting with the pulleys, a sliding spring actuated bar for actuating 35 the belt shifting device, said bar being provided with a notch and a wedge-shaped portion, and a sliding and swinging latch co-operating with the notch and wedge-shaped portion of said bar and operated from the reciprocatory frame.
18. In mechanism of the character de-
- scribed, the combination with a support, of a reciprocatory frame, a spindle journaled upon the frame, a flier co-operating with the spindle, a main drive shaft, gearing between 60 said shaft and flier, a secondary shaft, gearing between the secondary shaft and spindle, cone-pulleys upon said shafts, a belt connection between the pulleys, a sliding rod, a yoke upon said rod to shift the belt, a spiral cam rotatable upon the rod, an arm secured to the rod and in engagement with the cam, a ratchet wheel carried by the cam, a lever actuated by the frame, a pawl carried by the lever and engaged with the ratchet wheel, 65 tight and loose pulleys upon the drive shaft, a belt shifting device coacting with the pulleys, a spring projected bar for actuating the belt shifting device, a latch for controlling the movement of the bar, and means 70 mounted upon the ratchet wheel for operating the latch.
19. In mechanism of the character described, the combination with winding means, of a twisting device delivering thereto, 80 means for operating the twisting device including cone pulleys and a belt connecting the same, a shifting rod associated with the belt, a cam journaled on the rod, means for rotating the cam, an arm adjustable longitudinally along the rod and engaging the cam, and a device for holding the arm at different positions on the rod to vary the 85 twists of the material.
20. In mechanism of the character described, the combination with winding means, of a flier associated therewith, a shaft, spiral gears connecting the shaft and flier for effecting the positive movement of the flier, a tension rack associated with the flier, a belt connected to the shaft and to the winding means, shifting means for the belt including a shifting rod, a cam journaled on the shifting rod, means for rotating the cam, an arm adjustable along the shifting rod and 90 engaging the cam, and a thumb screw carried by the arm and engaging the rod to hold the arm in different positions on said rod, the adjustment of said arm varying the twists of the material.
- In testimony, that I claim the foregoing as my own, I have hereto affixed my signature in the presence of two witnesses.
- EDWARD D. STICKLER.
